UNITED STATES PATENT OFFICE

BROWNIE L. MARLIN, OF ST. LOUIS, MISSOURI

DESIGN FOR A DOLL

Application filed October 10, 1932. Serial No. 45,281. Term of patent 7 years.

To all whom it may concern:

Be it known that I, BROWNIE L. MARLIN, a citizen of the United States, residing at the city of St. Louis, State of Missouri, have invented a new, original, and ornamental Design for Doll, of which the following is a specification, reference being had to the accompanying drawing, forming part thereof.

Fig. 1 is a front view of the doll showing my new design.

Fig. 2 is a side view.

Fig. 3 is a rear view.

The lining for color indicates the background of black fabric which extends over the entire surface of the doll shown in each of the figures of the drawing.

I claim:

The ornamental design for a doll, as shown and described.

BROWNIE L. MARLIN.
